UNITED STATES PATENT OFFICE.

AUGUST G. KLEINT, OF FORT WAYNE, INDIANA.

DESIGN FOR A CHARM.

50,135.

Specification for Design.

Patented Jan. 2, 1917.

Application filed September 7, 1916. Serial No. 118,928. Term of patent 7 years.

To all whom it may concern:

Be it known that I, AUGUST G. KLEINT, a citizen of the United States of America, and resident of Fort Wayne, in the county of Allen and State of Indiana, have invented a new, original, and ornamental Design for a Charm, of which the following is a specification, reference being had to the accompanying drawing, forming part thereof.

I claim:

The ornamental design for a charm as shown.

AUGUST G. KLEINT.
